W. Lee Kelsoe

ATTORNEY

UNITED STATES PATENT OFFICE

EDWARD ZINN, OF NEW YORK, N. Y.

PERPETUAL CALENDAR

Application filed October 8, 1929. Serial No. 398,112.

The object of the invention is to provide an inexpensive perpetual calendar which may be made of light material such as cardboard; the movable elements being connected by a single fastening which serves as a pivot member, and the ensemble having somewhat the appearance of a clock front, and being so designed as to enable the carrying of advertising matter in addition to the necessary dials and pointer.

The device will be described with reference to the accompanying drawing, in which—

Figure 1 is a plan view of an embodiment of the invention, and

Figure 2 is a sectional elevation on the line 2—2, Fig. 1.

Referring to the drawings, it will be seen that the embodiment therein shown comprises a main body-member 1 of cardboard or the like. Formed integrally therewith, or separately if desired, is a day-number annulus 2, having printed thereon within sections bounded by radial lines the day-numbers reading one to thirty-one.

Pivoted upon the body member 1 is the day name annulus. On member 3 is printed in annular formation, with sections bounded by radial lines, the days of the week successively over a period of thirty one days or more. If desired, the day-number annulus may be fixed and the day-name annulus rotatable, it only being necessary to secure relative movement between the two.

The pivot member is a pronged fastener 4 extending through the body member, and having its prongs bent against the same. The fastener also pivotally supports the month disk 5, on which is printed a plurality of radial lines, the twelve spaces between the lines having printed thereon, at the top, the names of the twelve months. Below each month appears a legend indicating the number of days in that month.

Fastener 4 also serves as a pivot member for a pointer 6 which, in the present embodiment, is formed of a folded strip, so that two arms are provided, these arms embracing and being in frictional contact with the month disk, as shown in Fig. 2.

The body member may be provided with

easel supporting means, or with an eyelet 7, by means of which the device may be hung.

The operation of the calendar is as follows: At the beginning of a month, the pointer is swung into such position that its innermost end lies in register with the printed indication of the month, as for example, September, Fig. 1. The day-name annulus will then be rotated until the appropriate day-name, as for example, Sunday, is placed in register with the pointer at the left-hand lower end, as shown in Fig. 1. If the calendar is used on an office desk, for example, at the beginning of each day, or at the close of the preceding day, the pointer is moved, still frictionally engaging the month disk, one position, i. e., until the outermost end lies in register with 2, and this operation is followed until, as shown by the registration of the pointer with the month disk, the thirty days of September have passed. The pointer and month disk are then moved relatively so that the innermost end of the pointer comes into registration with October, which has thirty one days. Before moving the pointer, it may be noted that the 30th of September was Monday, this being shown by the outermost end of the pointer at the close of the month in register with section *a*, Fig. 1. After the required relative movement of pointer and month disk, it is only necessary to move the day-name annulus so that the indication "Tue", i. e., Tuesday, come into register with the numeral 1 at *b*.

It will be understood that various modifications may be made of the form and arrangement of the elements herein shown and described without departing from the spirit of the invention, for example, the front plate 7 may be omitted if desired. Also, when used, it may be secured to the body member 1 below dotted line C by glue or staples. In the drawing, the front plate at its lower margin is bent backwards upon the body member 1 and a lip 8 is passed through a slot 9 formed in member 1.

Having described my invention what I claim and desire to secure by Letters Patent is as follows:—

1. In a device of the character described,

a day-number member bearing numbers 1 to 31 in annular arrangement, a day-name member bearing the name of each day of a succession of weeks, in annular arrangement, 5 means for securing relative movement between the day-number and day-name members, a rotatable month-annulus bearing the name of each of the twelve months and the number of days of each, and a pointer having 10 one section adapted to lie in register with the day-name member, and a second section adapted to lie in register with the month disk.

2. A device constructed in accordance with 15 claim 1 in which the month disk and pointer are so related that movement of the latter carries with it the month disk.

3. A device constructed in accordance with claim 1 in which the pointer, month disk and 20 day-name member are secured to the day-number member by a common axial support.

4. A device constructed in accordance with claim 1 in which the pointer is formed with arms which embrace the month disk and engage 25 the latter with frictional contact.

In testimony whereof, I have signed my name to this specification.

EDWARD ZINN.
